(57) **CLAIM**

I claim the ornamental design for combined two compartment food and beverage container, as shown and described.

DESCRIPTION

FIG. 1 is a perspective view of combined two compartment food and beverage container showing our new design;

FIG. 2 is a top plan view thereof;

FIG. 3 is a front view thereof, the rear view being a mirror image;

FIG. 4 is a left side view thereof, the right side view being a mirror image;

FIG. 5 is a bottom plan view thereof;

FIG. 6 is a perspective view of an alternate embodiment of FIG. 1;

FIG. 7 is a top plan view of FIG. 6;

FIG. 8 is a front view of FIG. 6, the rear view being a mirror image;

FIG. 9 is a left side view of FIG. 6, the right side being a mirror image; and,

FIG. 10 is a bottom plan view of FIG. 6.

The dashed lines in FIGS. 1-10 represent environment and are for illustrative purposes only and do not constitute part of the claimed design. The phantom lines in FIGS. 1-10 define the border between claimed and unclaimed matter.
